UNITED STATES PATENT OFFICE

FREDERICK F. RAVLIN, OF MIAMI, FLORIDA

SUPPORT FOR SERVING TRAYS

Application filed October 4, 1932. Serial No. 636,245.

This invention is directed to a support for serving trays designed more particularly for use in connection with automobiles, and adapted for removable connection with the window glass pocket of a selected door to position the tray for convenient use within the automobile.

Tray supports of this character must combine certain essential requirements to be of commercial utility, as for example, the tray support must be capable of instant connection with the window glass pocket or removal therefrom; must support the tray to avoid interference with access to the door-pocket when the tray is in use; must not interfere with the raising or lowering of the window when in place; and must possess adjustability to compensate for different thicknesses of door wall inwardly of the pocket.

The present invention is designed to present and maintain the essential characteristics above mentioned, in that it provides for easy and quick connection or removal; will permit full window operation when in place; is sufficiently spaced from the inner side of the door to avoid interference with access to the door pocket; and is adjustable to compensate for different thicknesses of door wall while maintaining the rigidity and security of the support and the substantial level of the tray carried by the support.

The invention therefore consists in providing supporting arms to which the tray is rigidly or removably secured, with such arms including an inclined section overlying the inner surface of the door and terminating in hook-sections to engage over the free upper edge of the window pocket in the door; the inclined sections being provided with manually adjustable means for compensating for different thicknesses of the inner walls of window pockets.

The invention is illustrated in the accompanying drawing, in which:

Fig. 1 is a perspective view showing the improved support, the connected tray being broken away.

Fig. 2 is a side elevation of a slightly modified form of the invention.

Fig. 3 is a section on the line 3-3 of Fig.

2, showing the sliding cooperation of the compensating member and the support arms.

The improved support comprises supporting arms, 1, provided in duplicate and arranged in spaced parallel relation. The main length 2 of the arms are provided to support the tray or like element, such being here shown as a shallow tray 3, preferably, but not necessarily of metal and of sufficient surface area for the contemplated purpose. The tray 3 may be permanently secured to the sections 2 of the arms 1, though the invention contemplates to removable connection of the tray, if desired.

The sections 2 of the arms 1 extend beyond the relative inner edge 4 of the tray 3 for a desired distance, and the arms are then turned upwardly, presenting sections 5 which incline upwardly and toward the tray at approximately thirty degrees (30°) to the vertical. Obviously, more or less inclination is contemplated if desirable, though the indicated inclination is preferable for usual practice.

The arms 1 at the upper ends of the inclined sections 5 are extended forwardly as sections 6, which sections 6 are projected parallel with the sections 2 and therefore with the tray 3. The arms 1 are preferably of strip form, with the sections 2 and 5 on edge vertically, while the sections 6 are turned at right angles to the sections 5 to present flat bearing surfaces for cooperation with the wall of the window glass pocket. The sections 6 terminate in downwardly-turned hooks 7, designed to fit within the window glass door pockets and bear against the inner surface of the relatively inner wall 8 of such pockets. The hook terminals 7 are designed to avoid interference with desired movement of the window in the pocket while the hooks are in place.

The described inclination of the sections 5 of the arms 1, presents as lower forward bearing points 9 the junctions of the sections 2 and 5. These bearing points form the lower contact and supporting terminals of the tray support, and in the absence of other means would engage the inner surface of the door and hold the tray in position. With the inner

wall portion 8 of the window door pocket of varying thickness, as is a fact in different makes of automobiles, reliance on the points 9 as bearing points would naturally in thinner or thicker walls than those for which the construction was devised, result in an inclined position of the tray, and as such would render the device of little service, a particularly important feature of the present invention is the provision of means whereby the tray may be held level, while compensating for the varying thickness of walls 8.

The preferred form of such means is illustrated in Fig. 1, wherein the adjustable bearing contact is in the form of a bar 10, extending between the sections 5 of the support, and passing through slots 11 in such sections 5, the slots aligning with the sections. Beyond each section 5, the bar 10 is bent around the forward slot wall, as at 12, then projected forwardly, as at 13, and terminally formed with a lateral foot 14, preferably provided with a pad 15.

Through the medium of the inclined slots 11, the adjustable bearing contact foot 14 varies its horizontal advance according to its position lengthwise the slots, so that in positioning the tray as described, the adjustable bearing contact is moved in the slots until the feet 14, or more exactly the pads 15 thereon, contact with the inner surface of the door. As this adjustment follows a leveling of the tray, and the adjustment is made to insure bearing contact with the inner surface of the door, it follows that the tray will be maintained level and a securing support and bearing maintained regardless of the thickness of the inner wall 8 of the window pocket.

The form illustrated in Fig. 2 is a slight modification as to the adjusting compensating member. Here the arms, indicated at 16 are similar to the arms of the preferred form, such arms 16 having section 17 to support the tray 18, inclined sections 19, upper flat sections 20 having terminal hooks 21, with the respective parts arranged as described in the preferred form. The adjustable compensating bearing member in this modified form comprises a bar 22 extending between the sections 19, but instead of passing through slots in such section, are bent to embrace three sides of each section, as indicated at 23. Thus the compensating member has sliding and guided relation to the inclined sections 19 and is compelled to follow such sections in movement. The compensating member in the modified form extends forwardly at 24, with a terminal foot 25, having a pad 26.

The operation, function, and result of the modified construction is similar to that of the preferred form, as will be obvious.

The arms of the supports of both forms are preferably rigid relatively, and as the tray maintains this rigidity at one end, it is contemplated to connect such arms near the

opposite ends. Any means to this end may be employed, such being indicated as a transverse brace 27.

The lengths of the sections 2 of the arms 1 in advance of the tray toward the sections 5 will support the tray proper a sufficient distance from the inner surface of the door to permit free access to the usual door pocket while the tray is in use. Of course the tray so called is merely an illustration of an element to be carried by the arms, and no limitation is intended by the form shown, as other forms of trays, flat tables, or even receptacles may be readily employed.

Having thus described the invention, what is claimed as new, is:—

1. A tray and a support therefor, said support including tray-carrying arms having upstanding relatively inclined sections, said inclined sections terminating in hooks on the opposite side of said arms from their tray receiving portion, and members adjustable longitudinally of such inclined portions of the arms to provide a bearing contact for such support below and opposed to said hooks. 90

2. A tray and support therefor, said support including tray-carrying arms terminating in hooks, an intermediate portion of such arms being inclined relative to the vertical, and elements slidably cooperating with such inclined portions of said arms to form adjustable bearing contacts for the support, said elements being compelled to follow the inclined portions of the arms. 95

3. A tray and support therefor, said support including tray-carrying arms having terminal hooks, said arms having portions extending above the tray level and inclined with respect to the vertical and interposed between the tray level and the hooks, elements having sliding cooperation with the inclined portions of the arms, and bearing feet at the inner ends of said elements. 100

4. A tray and support therefor, said support including tray-carrying arms having terminal hooks, said arms including slotted relatively inclined portions between the tray level and the hooks, and bearing-contact members for the tray movable longitudinally of said inclined portions and guided in said slots. 110

5. A tray and support therefor, said support including tray-carrying arms having terminal hooks, said arms having relatively inclined portions between the tray level and the hooks, and contact bearing members movable longitudinally of such inclined arm portions for adjustment, said members being formed to partly enclose such inclined portions for guiding cooperation therewith. 120

In testimony whereof I affix my signature.
FREDERICK F. RAVLIN.
